UNITED STATES PATENT OFFICE

FRED R. TAISEY, OF LOWELL, MASSACHUSETTS, ASSIGNOR TO THE LAMSON COMPANY,
OF SYRACUSE, NEW YORK, A CORPORATION OF MASSACHUSETTS

CENTRAL-STATION APPARATUS

Application filed May 18, 1928. Serial No. 278,670.

This invention relates to central station apparatus useful in despatch systems wherein carriers for merchandise, papers, money, etc. are received at a central point from any of a plurality of outlying stations and from which 5 central station such carriers, after removal, exchange, or inspection of their contents, are returned to the respective sending stations. For purposes of illustration the invention is 10 herein explained as applied to the central station of a carrier despatch system of that type commonly employed in stores, and wherein the carriers are transmitted to and from the central station through pneumatic tubes. The patent to Whittier 1,365,428 15 dated January 11, 1921 may be referred to for a full discussion of the advantages of a proper relation of the activity of such a station to the central station facilities and for its 20 instances of improved central station handling of the traffic in a carrier-despatch system of this general type. However, while the apparatus of the Whittier patent is admirably qualified to perform its intended 25 function in an acceptable and efficient manner, its complexity and cost prevents its adoption in some establishments where, although the problem of handling carriers is similar to that described by Whittier, limitations of space and capital necessitate simplification of structure as compared with that of 30 Whittier.

In accordance with the present invention I provide central station apparatus of simple 35 and inexpensive type, but having sufficient flexibility of operation to permit economical attendance regardless of fluctuations in the volume of business.

In the accompanying drawings I have illustrated by way of example one desirable embodiment of the invention, together with certain modifications thereof, and in the drawings

Fig. 1 is a diagrammatic, fragmentary plan 45 view of a central station apparatus embodying the present invention;

Fig. 2 is a fragmentary diagrammatic front elevation of the left hand and central portions of the central station apparatus shown in 50 Fig. 1;

Fig. 3 is a vertical section to larger scale, substantially on the line 3—3 of Fig. 2;

Fig. 4 is a fragmentary side elevation illustrating a modified arrangement of the left-hand end of the central station apparatus; 55

Fig. 5 is a fragmentary plan view of the left-hand portion of the apparatus shown in Figs. 1 and 2;

Fig. 6 is a fragmentary vertical section on the line 6—6 of Fig. 2; and 60

Fig. 7 is a fragmentary vertical section on the same plane as Fig. 3, showing a preferred arrangement of carrier-distributing means at one side of the desk.

Referring to the drawings, the central 65 station apparatus is shown as comprising an elongate desk 1 of such a width that carriers resting upon its upper surface may readily be grasped by operators seated at either side thereof. While I have herein shown this 70 desk as continuous from end to end of the central station apparatus, it is obvious that it may be made in several independent sections if desired, and it is not at all essential 75 that all of its parts be in linear alignment.

Extending along the desk 1 is a series of pneumatic tube terminals, such series being divided as shown in Fig. 1 into the groups 2 and 3 of delivery terminals adjacent to the opposite ends respectively of the desk, a central group 4 of delivery terminals, and groups 5 and 6 of despatch terminals arranged respectively between the central group 4 and the end groups 2 and 3. The groups 5 and 6 of despatch terminals determine the positions of 85 cashiers' stations, indicated by the seats 7 and 8 for operators. Preferably, cashiers are arranged at opposite sides of the desk and there may be several cashiers at each of the stations 90 7 and 8, it being understood that the despatch terminals of the groups 5 and 6 are within reach of cashiers at stations 7 and 8 respectively.

Preferably the desk top is provided with 95 some means at the cashiers' stations to prevent carriers from rolling off. Such means may consist of substantially parallel rails 10 and 11 of such a height as to prevent carriers from rolling out and escaping from the space or channel between them, but of insufficient 100

height to interfere with the removal of the carriers by the cashiers. The top of the desk is flat and may constitute the support for the carriers in the space between the rails 10 and 11. If desired, such support may consist of a moving belt or other usual form of conveyor resting upon the upper surface of the desk or moving in a depression in such surface. On the other hand, in place of the spaced guard rails 10 and 11, the top of the desk may have a depression or channel therein, and when hereafter I refer to a "support" for the carriers at the cashiers' stations I intend to include any suitable means, whether movable or stationary, upon the carriers may rest in position to be grasped by the cashier.

The group 4 of delivery terminals substantially coincides with the position of the charge authorizer's station 9. Under ordinary circumstances, a single authorizer at one side of the desk may take care of all of the charge transactions but, if necessary, a second authorizer may be arranged at the opposite side of the desk, as shown at 9^a, in which event a certain portion of the charge carriers are diverted to the authorizer at the point 9^a by mechanism hereinafter more fully described.

Preferably each of the groups 5 and 6 of the tubes contains one special despatch terminal 12 through which carriers may be delivered to the authorizer's station, and a second tube 13 leading back from the authorizer's station to the cashier's station.

The delivery terminals of the group 4 are provided with separators for separating cash and charge carriers, and preferably the delivery terminals of the groups 2 and 3 are likewise provided with separators. Referring particularly to Fig. 3 I have indicated a pair of tubes 14 and 15 leading from outlying stations to the central group 4 of delivery terminals, each tube 14 and 15, as well as the others of the group being provided with a terminal structure indicated generally at 16. Each of these terminal structures comprises a separator device 17, 18, etc., the separators of alternate tubes being arranged in reverse relation as is usual in order to save space. As thus arranged, the cash carrier discharge nozzles 19 and 20 form adjacent inner groups, while the charge carrier delivery nozzles 21 and 22 form outer groups which are more widely separated. The nozzles 19 and 20 of the group of tubes 4 deliver their carriers into one or the other of a pair of downwardly divergent chutes or inclined guideways 23 and 24, (Fig. 2). The guideways 23 and 24 are so arranged that carriers sliding down them are delivered onto the desk at the cashier's stations 7 and 8 respectively.

On the other hand, charge carriers delivered from the nozzles 21 drop into one or the other of a pair of downwardly converging chutes or inclined guideways 25 and 26 (Fig.

2) from which carriers are discharged onto a suitable deflector 27 substantially opposite to the authorizer's station 9, and from which the carriers fall into a suitable pocket or depression 28 in the upper surface of the desk 1. Likewise charge carriers delivered from the nozzles 22 fall into one or the other of a pair of downwardly converging chutes 25^a which deliver the carriers onto an inclined deflector 29 down which they roll into the pocket 28.

While, as shown in Fig. 3, the deflector 29 may be of unitary and stationary character, I prefer to make this deflector as shown in Fig. 7. As thus constructed it comprises the upper stationary part 29^a, the lower stationary part 29^b, and the central movable part 30, pivoted at 31. The lower edge of the part 30 is hinged at 33 to a plate 32, which in turn is hinged at 34 to a plate 35 hinged at 36 to a portion of the desk structure. When the part 30 is aligned with the parts 29^a and 29^b it operates in the same way as the deflector 29 as shown in Fig. 3, but when the part 30 is swung to the position shown in Fig. 7 in dotted lines, an opening is left between it and the part 29^a through which carriers delivered from the chutes 25^a and 26^a drop onto the plate 32 which, with the part 35 and the lower part of the part 30, forms a pocket for receiving these carriers and from which they may be readily removed by the authorizer at the station 9^a. Any suitable retaining means, not shown, may be provided for holding the part 30 in the desired position.

I also arrange inclined chutes or guideways 37 and 38, respectively, adjacent to the opposite ends of the desk. If the delivery tubes of the groups 2 and 3 are provided with separators, I prefer to construct these chutes 37 and 38 as shown, for example, in Figs. 5 and 6. In this case each chute has the outer side walls 39 and 40 and intermediate partitions dividing it into three guideways 41, 42 and 43, the middle guideway 43 being wider than the outer guideways. In Fig. 6 I have shown a pair of tubes 44 and 45 (of the group 2 or 3), such tubes having the separators 46 and 47. These separators are so arranged that all of the charge carriers are delivered into the central channel 43, while the cash carriers drop into the channels 41 and 42 respectively. The lower end of the channel 43 is closed by a guard member 49 but just in advance of this guard the bottom of the channel has an opening 50 leading into a pneumatic pick-off tube 51 which extends to a point adjacent the authorizer's station where it may, as shown in Fig. 2, have a terminal portion 52 delivering carriers into the chute 25, it being understood that a similar tube connects the right-hand chute 38 with the authorizer's station.

As thus arranged, cash carriers 54 (Fig. 5) sliding down the chute 37, are delivered at the

cashier's station 7, while charge carriers 53 pass down into the tube 51 and are automatically delivered at the authorizer's station from which, after the proper transaction has been performed, they are despatched and returned to the cashier through the terminal 13.

In Fig. 4 I have shown a slight modification of the end chute of the desk. This chute is indicated at 37^a and provides but a single channel into which all carriers are delivered, the tubes of the group 2 being unprovided with separators. In this event the cashiers at the cashier's station pick up the charge carriers and transmit them through the terminal 12 to the authorizer's station.

In the above description no attempt has been made to include the minor details of construction which are common to central station apparatus of this general type, it being understood that such detail features as are necessary for the proper operation of such apparatus will be supplied in a manner well known to those skilled in the art. It is furthermore to be understood that while I have herein, for convenience, referred to cash and charge carriers, the terms cash and charge have been employed merely for convenience in designating carriers of two distinct classes and I do not intend by the employment of these terms to limit myself to the type of transaction which is to be performed or to the contents of the carriers of the two classes employed.

Obviously, various changes in detail in the proportions and arrangement of parts and the substitution of equivalent elements for those herein illustrated may be made without departing from the spirit of the invention and I contemplate that the principle of the invention may be found useful in apparatus employing a large or smaller number of terminal tubes and operator's stations than here illustrated.

I claim:

1. A central station apparatus comprising an elongate desk, a pair of gravity chutes extending lengthwise of the desk and arranged to deliver at points each substantially midway of the width of the desk but spaced longitudinally thereof, and means for discharging carriers of one class into one chute and carriers of another class into the other chute.

2. A central station apparatus comprising an elongate desk, a plurality of inclined guideways down which carriers may slide by gravity, said guideways extending longitudinally of the desk and delivering the carriers at points spaced lengthwise of the desk, respectively, a pneumatic tube for conveying carriers of different classes to the station, and means for separating said carriers by classes and for delivering carriers of different classes into different inclined guideways.

3. A central station apparatus comprising

ing an elongate desk having operators' stations at opposite sides thereof, means for conveying carriers of a plurality of classes to the central station, an inclined guideway extending longitudinally of the desk and into which carriers of one class are delivered and down which they slide onto the desk at a point within reach of both operator's stations, and another inclined guide which receives carriers of another class and along which said carriers slide to a point remote from said operators' stations.

4. A central station apparatus comprising an elongate desk, a series of carrier-delivery terminals, each terminal having means for separating carriers of one class from those of another, an inclined guideway for receiving carriers of one class, and a pair of inclined guideways arranged to receive carriers of the other class, all of said guideways extending longitudinally of the desk and having their delivery ends disposed intermediate the opposite sides of the desk.

5. A central station apparatus comprising an elongate desk, a series of carrier-delivery terminals, each terminal having means for separating carriers of one class from those of another, an inclined guideway for receiving carriers of one class, and a pair of inclined guideways arranged to receive carriers of the other class, the guideways of said pair sloping oppositely to the first-named guideway, all of said guideways extending longitudinally of the desk and arranged to deposit carriers at points substantially midway of the width of the desk.

6. A central station apparatus comprising an elongate desk, a series of carrier-delivery terminals, each terminal having means for separating carriers of one class from those of another, an inclined guideway for receiving carriers of one class, and a pair of inclined guideways arranged to receive carriers of the other class, the guideways of said pair being substantially parallel and sloping oppositely to the first-named guideway, all of said guideways extending longitudinally of the desk.

7. A central station apparatus comprising an elongate desk, a series of carrier-delivery terminals, each terminal having means for separating carriers of one class from those of another, an inclined guideway for receiving carriers of one class and a pair of inclined guideways arranged to receive carriers of the other class, and means for directing carriers delivered from the guideways of said pair to a common point, all of said guideways extending lengthwise of the desk.

8. A central station apparatus comprising a series of carrier-delivery terminals, each terminal having means for separating carriers of one class from those of another, an inclined guideway for receiving carriers of one class and a pair of inclined guideways arranged to receive carriers of the other class,

and means operating alternatively to direct carriers delivered from the guideways of said pair to the same or different points respectively.

5 9. A central station apparatus comprising an elongate desk, a series of carrier-delivery terminals, each terminal having means for separating carriers of one class from those of another, an inclined guideway for receiving carriers of one class and a pair of inclined

10 guideways arranged to receive carriers of the other class, all of said guideways extending longitudinally of the desk, and conveyor means for receiving all carriers from the 15 single guideway and for delivering them to a point remote from that at which carriers are delivered by the pair of guideways.

10 10. A central station apparatus comprising an elongate desk, a series of carrier-delivery terminals, each terminal having means for separating arriving carriers of one class from those of another, a pair of downwardly convergent chutes arranged to receive carriers of one class from the separating means, and a 25 pair of downwardly divergent chutes arranged to receive carriers of another class from the separating means, all of said chutes extending longitudinally of the desk and having their delivery ends intermediate the 30 sides of the desk.

11 11. A central station apparatus comprising a series of carrier-delivery terminals, a pair of inclined guideways, means associated with said terminals for delivering carriers 35 from some terminals into one guideway and from other terminals into the other guideway, and means operative to divert carriers from both guideways to a common point or alternatively to separate points.

40 12. A central station apparatus comprising a series of carrier-delivery terminals, a pair of inclined guideways, means associated with said terminals for delivering carriers from some terminals into one guideway and 45 from other terminals into the other guideway, and a deflector comprising jointed parts adapted, when its parts are disposed in one relation, to direct carriers from one guideway to the point of delivery of carriers 50 from the second guideway, and when disposed in another relation to direct carriers from the first guideway to another point.

13. A central station apparatus comprising an elongate desk, a cashier's station and 55 a charge authorizer's station, said stations being spaced longitudinally of the desk, a pair of inclined guideways down which carriers slide by gravity, the carriers from one guideway being delivered to the cashier's station and the carriers from the second guideway being delivered to the authorizer's station, and means for depositing cash carriers in the first-named of said guideways and charge carriers in the second of said guideways, the delivery ends of all of said guideways being substantially midway of the width of the desk.

14. A central station apparatus comprising a desk having a support for carriers, said support being accessible to a cashier's station at the side of the desk, a group of delivery terminals to the right and to the left respectively of the cashier's station, each terminal having means for separating charge and cash carriers, and downwardly converging inclined chutes arranged to deliver carriers to the support, the cash carriers only delivered by the terminals of both groups, sliding down said chutes onto said support.

70 15. A central station apparatus comprising a desk having a support for carriers, said support being accessible to a cashier's station at the side of the desk, a group of delivery terminals to the right and to the left respectively of the cashier's station, each terminal having means for separating charge and cash carriers, and downwardly converging inclined chutes arranged to deliver carriers to the support, the cash carriers delivered by the terminals of both groups sliding down 75 said chutes onto said support, and a chute inclined away from the cashier's station and arranged to receive charge carriers from at least one terminal of said group.

80 16. A central station apparatus comprising a series of carrier-delivery terminals, each terminal having means for separating arriving carriers of one class from those of another, an operator's station at substantially the middle of said series, inclined guideways 85 sloping downwardly in opposite directions toward the operator's station, said guideways receiving all carriers of one class, delivered by the terminals of said series, and guiding them to the operator's station, and other inclined guideways sloping downwardly in opposite directions and away from the operator's station, said latter guideways receiving all carriers of a second class delivered by the terminals and guiding them away from 90 the operator's station.

95 17. A central station apparatus comprising two operators' stations, two groups of delivery terminals, one group at least being provided with means for separating carriers 100 into two classes, a pair of chutes inclining toward one operator's station for delivering carriers to the latter and an inclined chute for delivering carriers to the other operator's station, one chute of the pair receiving all 105 carriers from one group of terminals and the second chute receiving all carriers of one class only from the other group of terminals, carriers of the other class from the latter group being deposited in the chute leading to 110 the second operator's station.

120 18. A central station apparatus comprising an elongate desk having a charge authorizer's station intermediate its ends, and cashiers' stations at opposite sides of the authorizer's 125

- station, groups of carrier-delivery terminals adjacent to the middle and to the opposite ends respectively of the desk, the terminals of the central group, at least, comprising means for separating cash and charge carriers, an inclined chute adjacent to each end of the desk, said chutes sloping downwardly toward the adjacent cashiers' stations respectively, oppositely inclined chutes at the center of the desk diverging toward the cashiers' stations respectively, a pair of inclined chutes at the center of the desk converging downwardly toward the authorizer's station, the terminals of the end groups delivering their carriers into the end chutes and the terminals of the middle group delivering cash carriers into the diverging central chutes and the charge carriers into the converging central chutes. 5
19. A central station having a charge authorizer's station and cashiers' stations at opposite sides of the authorizer's station, groups of carrier-delivery terminals adjacent to the authorizer's station and to the cashiers' stations respectively, the terminals of the central group, at least, comprising means for separating cash and charge carriers, inclined end chutes, said chutes sloping downwardly toward the adjacent cashiers' stations, respectively, oppositely inclined central chutes adjacent to the authorizer's station, said latter chutes diverging toward the cashiers' stations respectively, a second pair of inclined central chutes converging downwardly toward the authorizer's station, the terminals of the end groups of terminals delivering their carriers into the end chutes and the terminals of the middle group delivering cash carriers into the diverging central chutes and charge carriers into the converging central chutes, and means for transmitting charge carriers delivered from each end group of terminals to one of the converging chutes at the authorizer's station. 10
20. A central station apparatus comprising an elongate desk having a charge authorizer's station intermediate its ends, and cashiers' stations at opposite sides of the authorizer's station, groups of carrier-delivery terminals adjacent to the middle and to the opposite ends respectively of the desk, the terminals of the central group, at least, comprising means for separating cash and charge carriers, an inclined chute adjacent to each end of the desk, said chutes sloping downwardly toward the adjacent cashiers' stations, respectively, oppositely inclined chutes at the center of the desk diverging toward the cashiers' stations respectively, a pair of inclined chutes at the center of the desk converging downwardly toward the authorizer's station, the terminals of the end groups delivering their carriers into the end chutes, respectively, and the terminals of the middle group delivering cash carriers into the diverging central chutes and charge carriers into the converging central chutes, the end chutes having separate guideways for charge and cash carriers, and a pneumatic tube arranged to receive the cash carriers from the guideway of each end chute and to transmit such carriers to one of the converging chutes at the authorizer's station. 15
- Signed by me at Boston, Mass., this 3rd day of May, 1928.
